UNITED STATES PATENT OFFICE.

FREDERICK E. RUDOLPH, OF CHICAGO, ILLINOIS.

ADJUSTABLE SURFACER.

1,165,452.

Specification of Letters Patent. Patented Dec. 28, 1915.

Application filed September 7, 1915. Serial No. 49,321.

To all whom it may concern:

Be it known that I, FREDERICK E. RUDOLPH, a citizen of the United States, residing at Chicago, in the county of Cook and State of Illinois, have invented certain new and useful Improvements in Adjustable Surfacers, of which the following is a specification.

My invention relates to adjustable means for surfacing objects having generally rounded contours.

One of the objects of my invention is to provide means for holding a sheet of abrading material, such as emery cloth, sand paper or the like, which is quickly adjustable to present a surface that will conform to the surface to be dressed or trued up by the device, to thereby provide a backing for the abrading sheet to be carried thereby.

20 A special object of my invention is to provide a device for truing up and polishing the cylindrical working surface of a rotating commutator, of a dynamo electric machine, capable of adjustment to provide a 25 concaved surface, corresponding to and substantially concentric with the convex surface of said commutator, and means for holding a sheet of abrading material in position overlying the backing up surface of 30 the device.

Other and more specific objects of my invention will become readily apparent to persons skilled in the art, from a consideration of the following description when taken in 35 conjunction with the drawings, wherein:

Figure 1 is an elevation of a broken-away portion of the commutator showing the surfacing block applied thereto. Fig. 2 is an end view of the block. Fig. 3 is a section 40 taken on line 3—3 of Fig. 2. Fig. 4 is a section taken on line 4—4 of Fig. 3. Fig. 5 is an elevation of one form of the laminae or sheets of insulating material of which the block is largely composed. Fig. 6 shows a 45 modified form of the laminae and one form of the insulated guiding portions for the laminae. Fig. 7 is a section taken on line 7 of Fig. 3.

In all the views the same reference characters are employed to indicate similar parts.

The block 10, is shown in Fig. 1, as applied to the commutator 11. The block is composed of a series of perforated laminae 55 or sheets 12, of insulating material, each sheet having one or more perforations, such

as 13, 14, and 15, or having a single perforation 16 as shown in the modification. In Fig. 4, there are three guiding blocks 17, 18 and 19, for the perforations 13, 14 and 15, 60 respectively. The perforations, in every instance, are vertically of larger dimensions than, but of the same transverse dimensions as are the guiding blocks, so as to permit some vertical or longitudinal relative shifting of the insulated, laminated sheets 12 and 65 to prevent lateral shifting thereof. The guiding blocks 20 and 21 are adapted for the laminae shown in Fig. 6, this composite structure being a modified form of those 70 shown in Fig. 4, and is adapted for blocks of smaller dimensions. The sheets 12, composing the laminated structure of the blocks, may well be made of vulcanized fiber each about 1/64 of an inch thick, but I prefer to 75 have a thicker sheet of fiber at the terminal ends of the assembled inner sheets, such as shown at 22 and 23. Metal terminal plates 24, such as shown in Fig. 2, one on each side of the block, are perforated for the clamping screws 25—25'.

The guiding blocks 17, 18 and 19, shown in Figs. 3 and 4, are rectangular in cross section. The longer portion 17 is transversely perforated to receive a metal screw 85 threaded plug 26, to receive the longer clamping screws 25. A similar plug 26 is transversely positioned in the block 21, shown in Fig. 6, and perforated and threaded to receive similar screws for the same 90 purpose. The blocks, such as 17, 18, 19, 20 and 21, respectively, have broken joints, as shown, so that the laminae, supported on the blocks, will not pass in between the confronting surfaces of the adjacent ends. 95

On each of the plates 24 is mounted a spring pressed clip 27, having their front ends normally held away from the plate 24, by means of springs 28. Said clips are pivotally mounted upon pins 29 in brackets secured to the respective plates. A screw 30, having an oblong head 31 passes through a similar perforation 32, in the insulating plate 22, made oblong to prevent the screw from turning and then passes through the clip 27. A knurled threaded nut 31' passes over the screw 30, and serves as means for holding the front end of the clip 27 in more positive relation with the plate 24 to retain therebetween a sheet or fabric of abrading material 33, such as emery cloth, sand paper or the like. 105 110

To adjust and apply the device to a commutator, for the purpose of truing up the working surface of the commutator, the screws 25 are loosened and the front end 5 surface of the block is first applied to the commutator and each laminae is pressed toward the commutator from the rear end until the general contour contacting end of the block is substantially the same circumferential 10 configuration as the face of the commutator, at which time the clamping screws 25 are tightened to hold the laminated structure in adjusted position. A strip of sand paper 33 is then put under one clip 27, as shown in, 15 Figs. 1 and 3, and the other end of the strip is placed under the clip on the opposite side of the block. The thumb screws 31' are then turned to tighten the clips, when the device is ready for use.

20 By pressing the abrading sheet carried by the block 10 into firm contact with the commutator the surface of the commutator will thereby be perfectly trued by the abrading effect of the sand paper, emery cloth or the like. Should the commutator be of larger diameter, as shown by dotted lines 34, the block can be made to conform to the larger circumferential surface of the commutator in the same manner as heretofore described.

25 30 And thus the block may be used upon commutators of varying and various diameters. A block may be quickly and easily adjusted for commutators of various diameters, within a reasonable limit, and will thereafter 35 present a substantially uniform continuous surface, concentric with the surface of the commutator to be trued, and serving as a backing for the abrading paper or cloth used for the purpose, whereby the entire surface 40 of the paper or cloth may be brought into contact with the commutator.

45 It will be observed that all of the metallic parts of the block when in use are perfectly insulated from the commutator and for this reason the block may be used for truing purposes while the armature is energized, if so desired, without danger of short circuiting any parts of the armature by accidental con-

tact of the metal parts with the commutator thereof.

50

While I have herein shown and described a preferred embodiment of my invention, and one modification thereof, for the purpose of clear disclosure, it will be manifest that my invention is susceptible of many other 55 modifications, not shown, and within the scope of the appended claims.

Having described my invention, what I claim is:

1. A device of the character described 60 comprising a series of perforated, parallel, longitudinally movable relatively thin sheets of insulating material; a guide for said sheets within said perforations, to permit relative longitudinal movement and to prevent lateral movement thereof said guide comprising two longitudinally alining parts; means comprising alining screws taking through opposite ends of the guide and screw, threaded into only one part 70 thereof to clamp and hold the sheets by frictional engagement; a clip on each side of the device near one end, to engage and hold a sheet of abrading fabric over said end of the device and means to tighten the clip over 75 said fabric.

2. A device of the character described comprising a series of perforated, parallel longitudinally movable sheets of insulating material; metal terminal plates; guides 80 within said perforations, comprising two parts relatively movable, one said part of each guide secured to one terminal plate; a screw passing through the opposite terminal plate and the other guiding part of each 85 guide and into the companion part thereof, whereby to clamp the parts together and a fabric engaging clip on each said terminal plate.

In testimony whereof I hereunto set my 90 hand in the presence of two subscribing witnesses.

FREDERICK E. RUDOLPH.

In the presence of—

MARY F. ALLEN,
FORÉE BAIN.
